CLAIM

The ornamental design for a water bottle, as shown and described.

DESCRIPTION

FIG. 1 is a top, front isometric view of a water bottle showing my new design;

FIG. 2 is a front elevational view of the water bottle shown in FIG. 1.

FIG. 3 is a back side elevational view of the water bottle shown in FIG. 1, the left side being a mirror image of the right side.

FIG. 4 is a left side elevational view of the water bottle shown in FIG. 1, the left side being a mirror image of the right side.

FIG. 5 is a right side elevational view of the water bottle shown in FIG. 1, the left side being a mirror image of the right side.

FIG. 6 is a top plan view of the water bottle shown in FIG. 1; and,

FIG. 7 is a bottom plan view of the water bottle shown in FIG. 1.

The broken lines in the drawings depict portions of the water bottle that form no part of the claimed design.
